CLAIM

The ornamental design for a flower stand, as shown and described.

DESCRIPTION

FIG. 1 is a top, front, right side perspective view of a flower stand embodying the new design, with a flower shown in broken lines as environmental;

FIG. 2 is front elevation view thereof, the rear elevation view being a mirror image;

FIG. 3 is a left-side elevation view thereof, the right-side elevation view being a mirror image;

FIG. 4 is a top plan view thereof;

FIG. 5 is a bottom plan view thereof; and,

FIG. 6 is a top, front, right side exploded perspective view thereof.

The broken lines are included for the purpose of illustrating the environmental matter and form no part of the claimed design.

1 Claim, 4 Drawing Sheets
